CHAIN CANDLE

Siegfried Steinhart, 14 Obere Ganshalde,
8908 Krumbach, Germany

Filed Jan. 9, 1974, Ser. No. 432,038

Claims priority, application Germany July 19, 1973

Term of patent 14 years

Int. Cl. D26—04

U.S. Cl. D73—1 B

The figure is a side perspective view of a chain candle showing my new design, the appearance being the same from all sides.

I claim:

The ornamental design for a chain candle, as shown and described.
